UNITED STATES PATENT OFFICE

104,988

DESIGN FOR A TEXTILE FABRIC

Jonathan W. Brooks, Philadelphia, Pa.

Application May 12, 1937, Serial No. 69,308

Term of patent 3½ years

To all whom it may concern:

Be it known that I, Jonathan W. Brooks, a citizen of the United States of America, residing in the city of Philadelphia, Pennsylvania, have invented a new, original, and ornamental Design for a Textile Fabric, of which the following is a specification, reference being had to the accompanying drawing, forming part thereof, wherein, the figure is a plan view of a piece of textile fabric showing my new design.

I claim:

The ornamental design for a textile fabric substantially as shown.

J. W. BROOKS.
